Design for the Handles of .

Table Spoons and Forks.

Patented July 16, 1861.

Albert McNamee

Dec. 1439

John Gorham, Gorham Thurber and
Lewis Dexter, Jr., of Providence, R. I.
Letters Patent No. 74, dated July 16, 1861.

Whole No. 1439

The schedule referred to in these Letters Patent and making part of the same:

To all whom it may concern:

Be it known that we, John Gorham, Gorham Thurber and Lewis Dexter, Jr., of Providence, in the State of Rhode Island, have invented or produced a new and original design for the handles of Table Spoons and Forks, and we do hereby declare that the following is a full, clear and exact description thereof, reference being had to the accompanying drawings, making part of this specification; in which-

Fig. 1, is a plan of the upper surface, and

Fig. 2, a like view of the under surface.

Fig. 3 and 4, are cross sections taken at the narrowest and at

2

Mar. 14/39

the widest part of the handle.

In figures 1 and 2. of the accompanying drawings a, represents the stem of the handle either of a spoon or fork, and b, the enlarged end thereof. The stem is gradually but slightly increased in width from about the middle of its length towards each end, the swell being more sudden at c, where it joins the bowl, or fork. At the rear extremity of the stem, where the enlarged part b, commences, it spreads out on each side, with a rounded shoulder d, d, and then gradually spreads out in concave lines, as at e, e, these lines gradually becoming convex, to the widest part, where they run back and inwards, as at f, f, finally uniting to form a nearly semi circular end. Along each edge there is a small rounded moulding g, g, and just within this a row of beads h, h, and at the shoulders d, d, the mouldings g, g, that look like wires are united by two rosettes having somewhat the appearance produced by twisting together the ends of wires to unite them.

And at the rear end the . . . . mouldings from each side are turned into a rosette, the two rosettes as at i, i, coming in contact . . . . with a small rounded tip j, making the central finish. Between the rows of beads . . . . the surface is swelled as at k, figure . . . . k, this swell being gradually flattened towards the widest part of the handle.

That we claim as new and desire to secure by Letters Patent, is the design herein specified for the handles of spoons and forks, as set forth and represented.
